(57) **CLAIM**

The ornamental design for an anti-mosquitos clip, as shown and described.

DESCRIPTION

FIG. 1 is a top left side isometric view of an anti-mosquitos clip in accordance with the new design;

FIG. 2 is a top isometric view thereof;

FIG. 3 is a bottom right side isometric view thereof; and,

FIG. 4 is a bottom isometric view thereof.

The broken lines shown in FIGS. 3 and 4 are for illustration purposes only and form no part of the claimed design. The dashed line along the outer perimeter in FIGS. 1-4 illustrates stitching.
